UNITED STATES PATENT OFFICE

HARRY R. PRIEST, OF LOUDONVILLE, OHIO

COMBINATION TOOTH INSPECTING MIRROR AND FLOSS CAP

Application filed April 10, 1931. Serial No. 529,193.

This invention relates to combination tooth inspecting mirrors and floss caps, and has for an object to provide a small compact device of this type which may be conveniently carried in ladies' handbags as well as in the pocket.

A further object is to provide a pair of disk mirrors one of which is carried by a cylindrical cap which, when applied with its open side against the tongue, is firmly held in place by the tongue projecting into the cap so that the reflected images of the backs of either the upper or lower teeth may be conveniently viewed in the companion mirror held in front of the user's face.

A still further object is to provide an assembly of a pair of disk mirrors one of which is provided with a cylindrical flange open at one end to rest upon the tongue of the user, while the companion mirror may be mounted on a suitable grip, such as, for instance, the end of a tooth brush handle opposite the cleaning and polishing element of the handle.

A still further object is to provide tooth inspecting mirror and a dental floss cap assembled in a single unitary structure, the floss cap being of sufficient magnitude to receive a refill floss cap containing about 108 feet more or less of floss, the entire device being of substantially one and one-half inch more or less in length to provide a small compact assembly of the parts.

A still further object is to provide a novel cutter for the floss cap to eliminate the objectionable clogging of the usual cutter with floss wax and ends of floss, with consequent difficulty in cutting off a length of the floss.

With the above and other objects in view the invention consists in certain novel details of construction and combinations of parts hereinafter fully described and claimed, it being understood that various modifications may be resorted to within the scope of the appended claims without departing from the spirit or sacrificing any of the advantages of the invention.

In the accompanying drawings forming part of this specification,

50 Figure 1 is a perspective view showing the

mirrors in use to view the backs of the lower teeth,

Fig. 2 is a similar view, showing the position of the tongue-engaging mirror when viewing the backs of the upper teeth, 55

Fig. 3 is a detail perspective view showing the component parts of the device separated,

Fig. 4 is a longitudinal sectional view through the device,

Fig. 5 is a side elevation, partly broken away, of a modified form of the invention, 60

Fig. 6 is a longitudinal sectional view through a modified form of the floss cap with mirror, and

Fig. 7 is an end elevation of the device shown in Fig. 6, with the cutter in operation. 65

Referring now to the drawings in which like characters of reference designate similar parts in the various views, the preferred embodiment of the invention is shown to comprise a cap 10 which is open at one end to receive a dental floss refill container 11 adapted to hold about 108 feet of floss. The opposite end of the cap is interiorly threaded, as shown at 12. 70

A coupling disk 13 is provided on opposite sides with bosses 14 and 15, the boss 14 being recessed to receive a disk mirror 16 which may be either plain or of the magnifying type. Both bosses are exteriorly threaded, as shown respectively at 17 and 18. The boss 15 is screwed into the cap 10 and the latter forms a grip for holding the mirror in the fingers in front of the face, as shown by way of example in Fig. 1. 80

A disk mirror 19 is provided for viewing the backs of the teeth, and is mounted in the end of a cylindrical cap 20, the end 21 of the cap being recessed, as shown, to receive the mirror. The opposite end of the cap is open and is interiorly threaded, as shown at 22. When not in use, the cap 20 is screwed onto the exteriorly threaded boss 14 of the coupling disk 13 and when thus assembled 90 as best shown in Fig. 4, the entire device is of such dimensions as to occupy a space of about one and one-half inches more or less long and approximately half an inch more or less wide, so that the device may be 100

conveniently carried in a handbag or in the pocket of the user.

It will be noted, as best shown in Fig. 3, that the peripheral edge 23 of the coupling disk 13 is provided with flat faces and is preferably an octagon in contour so as to be firmly gripped by the fingers when manipulating the mirror 16 in front of the face.

By now referring to Figs. 1 and 2, it will be seen that the open ended cap 20 is in reality a flange projecting from the peripheral edge of the mirror 19, the purpose of which is to receive the surface of the tongue when the mirror is placed in the mouth so that the tongue may be moved about without dislodging the mirror in order to properly position the mirror to view the backs of the lower teeth, as shown in Fig. 1, or the backs of the upper teeth, as shown in Fig. 2.

Fig. 5 shows a modified form of the invention but, in this instance, the mirror 24 to be held in front of the face is preferably countersunk in the end of the grip or handle 25 of a tooth cleaning and polishing device, the opposite end of which is equipped with a cleaning and polishing element, designated in general by the numeral 26. The mirror 27, to be placed in the mouth, is, as above described, countersunk preferably in the end wall 28 of a cylindrical cap 29 which forms a flange to receive the tongue. The open end of the cap is interiorly threaded, as shown at 30, to receive exterior screw threads 31 formed on the end of the handle 25.

In Fig. 6 there is shown another modification of the invention, in which the floss cap 32 is of sufficient magnitude to contain about 108 feet of floss 33, and is open at the top to receive the flange 34 of a cap 35 in the end face of which is countersunk a tooth inspecting mirror 36.

In the modified forms of the invention shown in Fig. 4 and Fig. 6, preferably I employ a novel cutter for the floss, shown best in Fig. 7. The cutter comprises a plate 37 which is provided with a finger dip 38 and is adapted to be secured to the outer face of the end wall of the dental floss cap in any preferred manner. A lug 39 projects from one edge of the plate and is formed integral therewith. The lug is offset, as shown at 40, at its juncture with the plate to receive underneath the offset portion the extremity 41 of the dental floss. The edges of said offset portion may be sharpened if desired, although this is not essential. Said offset portion also elevates the rounded flat tip 42 of the lug above the plane of the base. In operation, the length of dental floss to be cut off is drawn from the opening 43 in the cap and passed underneath the offset portion 40 of the cutter to the opposite side thereof and thence drawn forwardly, as shown, whereupon a quick jerk will cause the edge of the offset portion 40 of the cutter to sever the desired

length of floss from the supply in the cap.

By virtue of the cutter being offset from the base thereof, clogging of the cutter with wax and odd ends of the floss will be prevented, while also the bend in the length of floss to be cut off, caused by directing the same around the offset portion 40 of the cutter and thence over the tip 41 of the cutter, permits of a clean cut being made, regardless of whether there is an accumulation of wax and odd ends of the floss underneath the cutter. Either edge of the cutter may be used to sever the length of floss from the supply with equal facility.

While in the above description I have designated screw threads forming the connecting means between the various elements of the device, it is to be understood that smooth slip joints may be substituted therefor without sacrificing any of the advantages above pointed out.

Having thus described the invention, I claim:

1. In combination, a pair of tooth inspecting mirrors, a floss cap having a closed end recessed to receive one of the mirrors, and a grip operatively connected to said cap and carrying the other of said mirrors within said cap.

2. In combination, a pair of tooth inspecting mirrors, a cap open at one end and supporting one of said mirrors in the opposite end, a cap forming a combined floss receptacle and grip, a dental floss container in the last-named cap, and a coupling disk uniting both of said caps and supporting the other of said mirrors within the first-named cap.

3. In combination, a pair of tooth inspecting mirrors, a cap supporting one of the mirrors and forming a marginal flange on one side of the mirror adapted to receive the tongue of the user for firmly anchoring the mirror against dislodgment when the tongue is moved to dispose the mirror to reflect the backs of the upper or the lower teeth, and a grip removably connected to said flange and carrying the other of said mirrors.

4. In combination, a pair of tooth inspecting mirrors, a cap open at one end and closed at the opposite end to receive one of said mirrors, a second cap forming a receptacle, a dental floss container in said receptacle, and a coupling flange having bosses on the opposite faces removably engaged in both of said caps to unite the caps, one of said bosses being recessed to receive the other of said mirrors and dispose the same within the first-named cap, the peripheral edge of said coupling disk having flat surfaces formed thereon to facilitate firmly gripping the same in the fingers for manipulating the last-named mirror in front of the face.

5. In combination, a pair of tooth inspecting mirrors, a cap open at one end and closed at the opposite end, said closed end of the

cap being recessed to receive one of said mirrors, a tooth cleaner and polisher having the end of the handle recessed and receiving the other of said mirrors, and a connection between said handle and said cap removably securing the cap to the handle.

6. A device of the class described comprising a dental floss cap open at one end, a tooth inspecting mirror having a flange received by said open end, and a cutter on the opposite end of the cap having an offset portion provided with opposite cutting edges and terminating in a rounded tip over which the floss may be directed from the cap during the cutting operation.

15 In testimony whereof I affix my signature.
